ABSTRACT OF THE DISCLOSURE

An apparatus having superimposed film and receiver sheets sealed around their peripheral edges to form a fluid-tight envelope. The envelope may include a pod or fluid container filled with processing fluid and a fluid trapping section spaced from the fluid container and including a highly absorbent pad for receiving excess fluid, the trapping section and envelope being separated by a rupturable seal. A process wherein developing fluid is injected into the envelope from the attached fluid container or by other means and a positive pressure is exerted on the envelope during a soak and development period to assure distribution of the fluid throughout the envelope and maintain the fluid and receiver sheets in spaced relation. At the end of this period the sheets are pressed together to bring them into intimate contact for image transfer. Such action ruptures the seal between the envelope and trapping section so that excess fluid is absorbed by the pad therein.

This invention relates to an improved process and product for use in image transfer photography.

Image transfer photography is well known in the art and products and apparatus for use with such photography have been commercially available for many years. Where, as is particularly desirable, the processing is to be done within a camera structure, it is essential that the processing materials be so confined or of such nature that they will not contaminate the interior of the camera. Where such process has been used for in-camera processing it has been customary, after exposure of the sensitized sheet or strip of film material, to apply a relatively thick, viscous processing fluid to the sheet adjacent the image area and to spread it across the image area in a uniform layer by progressively sandwiching the sensitized sheet with a sheet of transfer-image receiving material. One of the biggest problems with such materials and process has been in obtaining the desired uniformity of thickness of the viscous processing fluid. As is well known, any variation in thickness of such layer results in a variation in density in the finished transfer image. Moreover, when color materials are involved, any variation in thickness of the layer not only affects the density but also the relative color composition. As a result cameras using such a system have necessarily required the use of parts of relatively high precision. Moreover, the viscosity of the processing fluid tends to change appreciably with temperature, thereby affecting its spreading properties and tending to make it still more difficult to obtain uniformity of layer thickness under different temperature conditions. In addition, even with the viscous fluid used, it has been practically impossible to avoid some contamination of the processing apparatus used.

It is an object of this invention to provide an improved image-transfer film product, and a process for using this product, which will overcome these defects.

A further object is to provide such a product and process adapted to use a relatively free-flowing processing fluid so confined in the product during the processing

2

operation as to prevent contamination of the processing apparatus.

These and other objects are obtained by providing a sandwich construction wherein the film and transfer-image-receiving sheets or strips are either secured together around the edges of their image areas or are adapted to be held sealed together during processing so as to effectively form a fluid-tight envelope. During processing free-flowing processing liquid is injected into this envelope in sufficient quantities and under such pressure as to positively hold the opposed walls, which carry the image areas, spaced materially apart from one another throughout a predetermined "soak" period. At the end of this period the image areas are pressed together into intimate face-to-face relationship so that all excess liquid is forced from therebetween and are held in this relationship until image transfer has been completed. Preferably the sandwich incorporates a fluid trapping section which includes a pad of highly absorbent material isolated from the image areas during the soaking period and into which the excess fluid is forced when the image areas are pressed together for image transfer.

My improved process and several illustrative embodiments of my improved photographic product and apparatus for practicing this process are shown in the accompanying drawing wherein:

FIG. 1 is a plan view of an image transfer film sandwich construction embodying my invention;

FIG. 2 is a longitudinal section through the sandwich of FIG. 1;

FIGS. 3, 4, and 5 illustrate successive steps involved in using the sandwich of FIG. 1 in accordance with my improved process;

FIGS. 6 and 7 illustrate a slightly modified method of practicing my improved process;

FIG. 8 illustrates an alternative form of film product in accordance with my invention;

FIG. 9 is a longitudinal section through the sandwich of FIG. 8;

FIG. 10 illustrates one stage during the processing of a sandwich of the type shown in FIG. 8;

FIG. 11 illustrates another form of sandwich construction as well as the manner of processing this form;

FIG. 12 illustrates a slightly modified method of practicing a sandwich construction of the type shown in FIG. 11;

FIG. 13 shows a form of processing apparatus especially useful in practicing the improved process in accordance with my invention; and

FIG. 14 is a somewhat diagrammatic sectional view through a camera adapted for use with the materials and processing method in accordance with my invention.

An image transfer product in accordance with my invention is shown in FIG. 1 and comprises a sandwich 1 formed by superimposed sheets 2, 3 which are sealed together around their periphery as diagrammatically indicated by the X-hatched areas 4, 5, 6, and 7, in FIG. 1, whereby they form a fluid-tight envelope. Extending transversely across the sandwich near one end is an additional seal indicated at 8 adapted to isolate the image portion 9 of the sandwich from a trapping portion 10 located at one end thereof. Seal 8 is made considerably weaker than seals 4 to 7, so that it will rupture when a predetermined fluid pressure has been built up within the image portion of the envelope. Seal 8 may be formed in a manner similar to the rupturable seal on the pods of viscous processing fluid such as are commonly employed in commercially available image transfer products and which are described, for example, in U.S. Patent 2,543,181. At least those portions of the inner faces of sheets 2 and 3 which are outlined by the dash-dot line 11 in FIG. 1 constitute the useful image areas of the sheets, one of which is

photosensitive and the other of which is adapted to receive an image by transfer when processed in conjunction with the photosensitive area in the presence of an appropriate processing fluid. While either sheet could carry the photosensitive image area, I have shown sheet 2 as carrying the photosensitive image area designated 12, and sheet 3 as carrying the transfer-image-receptive area 13. In order to permit exposure of the photosensitive area at least one of the sheets must also be transparent to actinic rays. Again, for illustrative purposes, it is assumed that photosensitive sheet 2 is transparent and receiving sheet 3 is opaque.

Preferably the fluid-trapping portion 10 of the sandwich includes a pad 14 of highly absorbent material, such as blotting paper, cloth, gauze, or the like, which, as briefly explained above, will tend to rapidly absorb and hold the excess processing fluid.

It is intended that in processing the sandwich of FIG. 1, suitable free-flowing processing liquid 15 will be injected between the image areas 12 and 13 of sheets 2 and 3.

This may be accomplished with the aid of a suitable syringe 16, the tip 17 of which is adapted to pierce sheet 3 as illustrated in FIG. 3. Preferably, in order to facilitate this operation and to minimize the possibility of pushing the tip 17 through both sheets a porous pad 18 of loosely woven fibers, inert to the processing fluid, is provided between the sheets adjacent the seal 4. Pad 18 serves to hold the sheets 2 and 3 spaced slightly apart in this injection area and therefore affords a location easily recognizable by the user to indicate to him where the tip of the syringe should be inserted. Preferably during manufacture as much air as is practical is expelled from between sheets 2 and 3 so that, prior to use, they will, as shown in FIG. 2, lie in intimate face-to-face contact with one another throughout their entire area except, of course, in those areas carrying pads 14 and 18.

In using the film sandwich of FIG. 1 the photosensitive image area 12 is first exposed in a suitable camera or the like so as to produce a latent image therein. Thereafter, either in a darkroom or a dark chamber such as the interior of the camera, a predetermined quantity of free-flowing processing fluid is injected into the interior of the sandwich. For example, processing may be performed in a darkroom while the sandwich is supported on a suitable supporting member 20, the end portion 21 of which is preferably formed so as to support the injection area adjacent pad 18 raised slightly above the level of the image portion 9. As shown in FIG. 3 the tip 17 of syringe 16 is pushed through the sheet 3 and into the pad 18 and the syringe is then actuated to force its liquid processing composition through the pad and between the image areas 12 and 13.

In accordance with my invention the image areas 12 and 13 must be held spaced apart from one another throughout their extent for at least a predetermined soaking period and, in order to accomplish this result, when the syringe has been emptied, it is pulled out from the sandwich and pressure is applied to the outside of the envelope so as to build up an internal pressure within the fluid 15 throughout the interior of the image portion of the envelope. This may be conveniently performed with the aid of a suitable squeegee roller 22 which, as illustrated in FIG. 4 is rolled partly across the sandwich, starting at the left-hand end, and moved to a point slightly beyond the pad 18, thereby sealing off the injection opening 19 from the image portion and at the same time building up a slight internal pressure within the fluid 15 so as to hold the opposing walls of the envelope spaced from one another. This pressure is maintained for the desired soaking period, and then the squeegee roller 22 is again moved to the right so as to produce a relatively large increase in pressure in that fluid which has not been absorbed by the sheets, sufficient to cause rupture of the rupturable seal 8. During this soak period, fluid 15 is absorbed by both negative image area 12 and positive trans-

fer receiving area 13. The processing, which involves two major steps, begins and is carried out in accordance with any one of many well known diffusion transfer process techniques. An example of a silver salt diffusion transfer process which can be used is disclosed in U.S. Patent No. 2,352,014 to Rott. In such a process, as described in Example 5 thereof, for instance, development of the exposed silver halide takes place during a soaking period when the process fluid is present, as between the two sheets of the present invention. Continued movement of squeegee roller 22 across the surface of sheet 3 will then press the latter into intimate face-to-face contact with sheet 2 throughout the entire image area and forces all excess processing fluid into the absorbent pad 14 of trap 10. FIG. 5 illustrates the operation as the squeegee roller approaches the right-hand end of the image area, most of the excess fluid having already been forced into the pad 14 and the portion of the sheets behind the roller laminated together in face-to-face relationship. As in the Rott patent, supra, the unexposed silver halide or other image forming material is dissolved and transferred from the negative image area 12 and the positive transfer image receiving area 13. At the completion of the required image transfer period, the image portions of sheets 2 and 3 will be separated from one another so that the finished positive print now present on area 13 of sheet 3 may be obtained. This may be done, for example, by cutting around the image area of the sandwich as indicated at 23 and 24 in FIG. 1 and then peeling the sheets apart. Edge seals 6 and 7 may be either cut away or, preferably, will be of such nature that they may be readily stripped apart to facilitate such print separation.

Since the sheets 2 and 3 will ordinarily be quite flexible they will tend to bulge outwardly from one another quite readily even under the relatively low pressure applied to the fluid therein during the soaking period. Unless steps are taken to limit such bulging, there will therefore be required a rather considerable amount of processing fluid in excess of that needed to perform the actual photographic processing to ensure that the interior of the envelope is sufficiently filled to hold the image areas completely spaced throughout the soaking period. The amount of fluid required can be considerably reduced if sheets 2 and 3 are restrained against appreciable movement away from one another. FIGS. 6 and 7 illustrate the practice of my invention utilizing a backing member 25 for this purpose. This backing member 25 is shown as being provided with a pair of lateral supporting ribs 26 and 27 which are adapted to rest on the edge portions of the sandwich as illustrated in FIG. 7 to hold the backing surface 28 thereof at the desired spacing above support 20. As illustrated in FIG. 6 when roller 22 is advanced so as to build up and maintain the desired slight pressure in the fluid 15 during the soaking period, sheet 3 will be held by backing surface 28 at the desired spacing from sheet 2. Backing member 25 may be either positively held down or, as illustrated, may be made of sufficient weight that it will remain in position under the slight pressure used during the soaking period. At the end of the soaking interval, member 25 will be lifted out of the way and the process will continue as described above, roller 22 being rolled across the sandwich to rupture the seal 8, press the image areas together, and force the excess fluid into the absorbent pad 14.

FIG. 8 illustrates a somewhat modified form of sandwich construction which incorporates the processing fluid in compartment or chamber 31 forming part of the sandwich itself. This pod or chamber 31 is preferably at the opposite end of the sandwich from the fluid trapping chamber 32. Like the trapping chamber it is provided with a pressure-rupturable seal 33 isolating the processing fluid contents 34 from the central portion 37 bearing the image areas 35 and 36. Seal 33 is adapted to rupture when a predetermined pressure is built up in the fluid 34, so that the fluid may be injected between the image

areas 35 and 36 from the container 31. As before, the edges of the sandwich are sealed together as diagrammatically indicated at 38, 39, 40 and 41, these edge seals being appreciably stronger than the rupturable seal 33, as well as the rupturable seal 42 separating trap 32 from the image portion 37 of the sandwich.

This sandwich construction also illustrates another slight modification in that the upper and lower sheets of the sandwich are each built up from several sheet sections secured together in end-to-end relationship. This permits the use, in each portion of the sandwich, of materials which are best adapted for the particular function of that portion. Thus the composite upper sheet is formed by a left-hand end portion 43 which forms the upper wall of the fluid containing chamber 31 and which is secured as at 44 to the left-hand end of a sheet 45 of transfer-image-receptive material. The latter is in turn secured at its right-hand end as at 46 to another strip of sheet material 47 which serves as the upper wall of the fluid trapping section 32. Similarly the composite bottom sheet is formed of a left-hand section 48 forming the bottom of the fluid container 31 and secured as at 49 to a transparent sheet of photosensitive material 50. The opposite end of sheet 50 is in turn secured at 51 to a piece of sheet material 52 forming the bottom wall of the fluid trapping portion 32.

FIG. 10 illustrates one way of accomplishing my improved process using a sandwich construction of the type shown in FIGS. 8 and 9. After exposure, the sandwich is suitably supported in a darkroom or in a dark chamber such as the interior of a camera, and pressure is built up within the fluid 34 in container 31 sufficient to rupture seal 33 and to inject the fluid between the photosensitive and transfer image areas 35 and 36 of sheets 50 and 45 and to maintain the desired low positive pressure therebetween for the duration of the soaking period. Preferably, and as shown in FIG. 10 this operation is performed while sheet 45 is backed up by means of a backing member 25 so as to limit the tendency of the sheets 50 and 45 to bulge outwardly. The desired pressures may conveniently be built up and maintained by rolling a squeegee roller 22 from the left end of the sandwich across the container portion 31 to a position as shown in FIG. 10.

Sheets 45 and 50 are held apart from one another by the pressure within the fluid until the end of the soaking period, at which time member 25 is moved out of the way and squeegee roller 22 is once again moved toward the right across the sandwich, to cause rupture of seal 42 and to force the remaining excess fluid into the trap 32. As before this will also bring the transfer-receptive image area 36 of receiving sheet 45 into intimate face-to-face contact with the photosensitive image area 35 of sheet 50 so as to permit image transfer to obtain.

In each of the preceding cases the sandwich construction has included a pressure rupturable seal between the image portion and the trapping portion of the sandwich. However such a seal is not essential to the practice of my improved process so long as some means is provided to isolate the trapping portion from the image portion during the actual soaking period. FIGS. 11 and 12 show sandwiches which may otherwise be similar to those described above but in which the rupturable seal 8 or 42 is lacking. Instead, prior to injection of the fluid into the image portion of the sandwich, the upper and lower sheets are firmly pressed together into fluid-tight relationship along a line extending across the sandwich near the trapping section and held in this condition throughout the soaking period. This can be conveniently performed by means of a member 53 held thereagainst by force exerted in the direction indicated by the arrows. This alternative arrangement can obviously be used either with or without the use of the backing member 25, FIG. 11 illustrating the latter and FIG. 12 the former. Moreover it is obviously possible to combine

the functions of the pressure member 53 and the backing member 25. An apparatus using this type of construction, and which is especially adapted for practicing my improved process, is illustrated in FIG. 13.

This FIG. 13 apparatus includes a base or support 54 which movably carries a backing member 55 as by means of pairs of swingable links 56 and 57. Backing member 55 includes at its right-hand end a downwardly extending lip or pressure member 58 which, when the member 55 is swung down into operative position against a sandwich 59, as shown in FIG. 13, presses the upper sheet 60 thereof firmly against the lower sheet 61 to provide the desired seal. As long as the parts are in this relationship, trapping portion 62 of the sandwich is effectively isolated from the remainder thereof. In using this apparatus to practice my invention, the sandwich, after it has been exposed, is positioned on support 54 as shown in FIG. 13 and the member 55 is swung down into operative position. Conveniently a resilient catch 63 cooperating with a pin 64 may be used to maintain the desired pressure on the sealing lip 58. Fluid is then injected from the container portion 65 into the image portion of the sandwich as by means of a squeegee roller 22 as previously described, sufficient force being maintained on roller 22 so that the desired small positive pressure will be maintained in the fluid throughout the soaking period. At the end of this period member 25 will be swung out of the way and roller 22 rolled across the image portion to laminate the image areas together and to force the excess fluid into trapping portion 62 as previously described.

FIG. 14 diagrammatically illustrates a camera 70 of a type adapted for use in practicing my improved processing operation within the camera itself. Camera 70 is adapted to hold a supply roll 71 of a continuous strip of composite image transfer film product 72 which includes a plurality of sandwich portions 73, similar to those previously described, connected in end-to-end relationship with one another by connecting strip portions 74. Each sandwich preferably includes a fluid container 75 at its leading end, and a trapping portion 76 at its trailing end. The strip 72, including the sandwiches 73 is arranged to be threaded from the supply roll 71 past an exposure station 77, thence through a processing chamber 78 and out a suitable exit aperture 79. Suitably mounted within the processing chamber 78 is a squeegee roller 80 which is adapted to be traversed downwardly and rearwardly over the forward wall 81 of the chamber 78 by pulling an actuating knob 82, coupled to the roller, in the direction of the arrow 83. Also movably mounted within chamber 78, as by suitable swinging links 84 and 85, is a backing member 86 which includes a transversely arranged lip or sealing member 87 adjacent its lower end. As shown in FIG. 14, lip 87 is adapted to bear against a sandwich located in the processing chamber 78 so as to seal the trap 76 thereof from the image portion 88 during the soaking period. Backing member 86 may be swung from its operative position shown in FIG. 14 to a relatively raised position by swinging a lever 89, connected to link 84, in the direction of the arrow 90. Preferably a suitable toggle spring 91 is provided to hold backing member 86 in either its operative or inoperative position.

In using a transfer image product of the type under consideration, where the exposure is made through the sensitized sheet itself, the positive transfer image which would be obtained would normally be reversed, left to right, unless steps were taken to prevent this. In the camera illustrated this is done by providing a mirror 92 for reflecting the light passing through lens 93 onto the film product at the exposure station 77 and thereby effectively reversing the negative image. With such an arrangement the finished print will show the proper orientation. The camera also preferably includes a suitable cutter 94 adjacent the exit slot 79 for separating processed envelopes from the remainder of the strip.

In use, the end of the strip 74 protruding through opening 79 is grasped by the operator and pulled to an extent sufficient to bring the image portion of the first envelope into position for exposure at the exposure station 77. After exposure, the strip is again pulled sufficiently to move the exposed sandwich into processing position in chamber 78. This is the relationship actually illustrated in FIG. 14. Lever 89 is then swung in its counterclockwise direction to move backing member 86 into the operative positive position shown, with its rib 87 sealing the trap 76 from the image portion 88 of the sandwich. Knob 82 is then pulled so as to move roller 80 a sufficient distance to rupture the container 75 and force its contents into the image portion of the sandwich and to maintain the desired slight positive pressure therein. At the end of the predetermined soaking period lever 89 is swung clockwise to lift backing member 86 out of the way and knob 82 is pulled to the limit of its movement, during which roller 80 will move a sufficient distance to squeegee the image portions of the sheets of the sandwich firmly together and to force the excess processing fluid into the trap 76. Roller 80 may then be returned to its inoperative position by returning knob 82 to the position shown. At the end of the image transfer period the end of the strip is once again pulled to bring the now-processed sandwich out of the exist slot 79 so that it may be cut from the strip 72 and separation of the negative and positive image areas may be performed. This operation also moves the strip sufficiently to bring the next sandwich portion into exposure position.

My improved process is obviously substantially independent of the specific photographic image-transfer compositions and materials utilized except insofar as they affect the amount of processing fluid required for proper processing, and no detailed description of the specific materials is believed necessary in this application. Suffice it to say that almost any known image transfer materials could be utilized. For example, the sensitized sheet, the receiver sheet and the processing fluid itself may conveniently be of the type fully disclosed in the Canadian patent to Whitmore et al., 602,607, dated Aug. 2, 1960. Photographic materials of the type used in the presently commercially available image transfer films could likewise be used, except, of course, that the processing fluid itself should be substantially free-flowing rather than viscous as normally used with such commercial products. Both the sensitized and receiver sheets should preferably include at least one layer which is impermeous to the processing fluid and the inner walls of the fluid container itself should, of course, be of a material which will not react with the processing fluid. Suitable materials and techniques for obtaining these results are well known in the art and require no further description here.

It should be pointed out that, in order to best illustrate by invention, the relative thickness of the materials used has been greatly exaggerated in the drawing, particularly as regards the thickness of the layer of processing fluid. In practice therefore the fluid container and the trapping member will protrude above the general plane of the sandwich to a much lesser extent than as illustrated. It has been found, for example, that with materials of the type described in the abovementioned Canadian patent, the film and receiver sheets together will absorb, during the soaking period only about 5 cc. of processing fluid per square foot of area (of one sheet) over which the fluid is applied. This corresponds to a layer of fluid which, prior to soaking, would be only about .002 inch in thickness. However since it is desired that the opposing image areas be held completely out of contact with one another throughout the entire soaking period, the amount of processing fluid provided should be such that the layer of fluid over the image area at the beginning of the soaking period will preferably be 50 percent or more thicker than that required for the actual photographic processing. This in-

sures that soaking will be uniform over the entire image area. The excess fluid is, of course, squeegeed into the trapping portion of the sandwich and absorbed therein at the end of the soaking period, as previously described.

It is, of course, to be understood that the above example is but illustrative, and is in no sense intended to be limiting, since the actual amount of processing fluid required will, as mentioned before, depend to a considerable extent upon the particular photographic compositions and materials used in the sandwich. However for any particular materials the amount of fluid required for proper soaking may be readily determined and the amount provided should exceed such value sufficiently to keep the image areas spaced from one another throughout the soaking period.

While in the sandwich constructions illustrated, the edges and ends have been described as being positively bonded or sealed together prior to use, any or all of these seals could be eliminated and suitable pressure members could be provided for temporarily holding the corresponding areas of the sheets together during processing to form the desired fluid-tight envelope.

Other pressure means than a squeegee roller could also obviously be used to force the fluid into the image area and later into the trapping portion and the sandwich, rather than the pressure roller or other pressure means, could be moved to produce the desired fluid distribution and pressure.

Similarly many other changes could be made in the product and apparatus used in practicing my improved process without departing from the spirit and scope of my invention as defined by the appended claims.

I claim:

1. The method of processing a photographic product of the type comprising a first strip of sheet material having a photosensitive image area on one face thereof and a second strip of sheet material overlying said one face and having a transfer-image-receptive image area corresponding to and substantially coextensive with said photosensitive area and lying in substantial face-to-face contact therewith, said image areas being adapted for conjoint photographic processing in the presence of an appropriate processing liquid, said method comprising:

exposing said photosensitive image area to form a latent image therein; injecting a predetermined quantity of a free-flowing processing liquid between said image areas while confining said liquid between predetermined portions of said strips including at least those portions bearing said image areas; subjecting said confined liquid to, and maintaining it for a predetermined period under, a positive pressure sufficient to separate and to positively hold said image areas spaced apart from one another throughout their extent for the duration of said period; at the end of said period, releasing said confined liquid; and

pressing said image-area-bearing portions of said strips together, with said image areas once again in intimate face-to-face contact with one another.

2. The method as set forth in claim 1 wherein the said predetermined portions of said strips between which said liquid is confined are bounded at least in part by a seal, rupturable upon the pressure within said confined liquid reaching a predetermined value,

the pressure in said liquid throughout said period being maintained at a value below said predetermined rupturing value,

and wherein release of said liquid at the end of said period is produced by increasing the pressure therein to said rupturing value to rupture said seal.

3. A photographic product comprising a pair of sheets of fluid impervious material,

at least one of said sheets carrying on one face thereof a fluid absorptive image area, said other of said sheets being superimposed on said one sheet so that an area thereof overlies said image area in intimate face-to-face contact therewith throughout said areas, portions of said sheets surrounding said areas being sealed together to form a substantially fluid-tight envelope section enclosing said image area, at least certain portions of said envelope section being flexible to permit complete separation of said image area and the overlying area of said second sheet upon injection of a predetermined quantity of free-flowing processing liquid therebetween, one of said sealed portions being relatively weaker than the others whereby it will rupture upon generation of a predetermined pressure in such fluid within said envelope and release the excess processing fluid from said envelope section.

4. A photographic product as in claim 3 further comprising a trap for excess fluid separated from the interior of said envelope section by said rupturable seal.

5. A photographic product as in claim 3 wherein further portions of said sheets are sealed together to form a second fluid-tight envelope section alongside said first envelope section and separated therefrom by said rupturable seal thereby forming a trap for excess fluid released from said first envelope section.

6. A composite photographic product for image transfer use comprising

a first sheet, at least a portion of one face of which constitutes a photosensitive image area; a second sheet overlying said one face of said first sheet, that portion of said second sheet directly opposite said photosensitive image area constituting a second image area receptive to a transfer image when processed in conjunction with said photosensitive image area and a processing fluid; opposed portions of said sheets lying outside of said image areas being secured together to form a continuous fluid-tight seal completely surrounding said image areas, at least a portion of one of said sheets being flexible whereby said image areas are free to separate from one another throughout their entire extent without rupture of said seal upon injection of processing fluid therebetween, a selected portion of said seal being more readily rupturable than the remainder of said seal whereby said portion of said seal will rupture when fluid pressure between said areas exceeds a predetermined value.

7. The method of photographic processing involving the use of an envelope sealed completely about its peripheral edges and having opposed inner wall surfaces of fluid absorptive image-receptive material adapted for joint processing and one of which surfaces carries a latent image therein, comprising the steps of:

injecting between said image receptive surfaces a free-flowing processing liquid in such quantity and under such pressure as to hold said image-receptive wall surfaces spaced from one another for a first predetermined period, at the expiration of said period, removing the remaining unabsorbed liquid from between said surfaces, pressing said surfaces together in face-to-face relationship, and maintaining them thus for a second predetermined period, and thereafter separating said surfaces.

8. The method of photographic processing involving the use of an envelope having opposed inner wall surfaces at least one of which is of fluid absorptive, image-receptive material adapted for processing in conjunction with an appropriate free-flowing processing liquid comprising:

filling said envelope with such processing liquid suffi-

cient to maintain said surfaces spaced from one another for at least a predetermined period, holding said liquid within said envelope for such period and under such conditions that said liquid will maintain said surfaces thus spaced from one another throughout said period, at the end of said period; removing the unabsorbed liquid from between said surfaces, and pressing said surfaces into substantial face-to-face contact with one another.

9. The method of processing a photographic product of the type comprising a first strip of sheet material having a photosensitive image area on one face thereof and a second sheet overlying said one face, and having an area thereof corresponding to and substantially coextensive with said image area lying in substantial face-to-face contact therewith; said method comprising:

exposing said image area to form a latent image therein; injecting a sufficient quantity of a substantially free-flowing processing liquid between at least those portions of said strip bearing said areas to cause said areas to separate completely from one another throughout their extent; maintaining such fluid between said areas under a positive pressure for a predetermined processing period so that said fluid will hold said areas completely spaced from one another throughout said period; at the end of said period; relieving the pressure on said liquid; and pressing those portions of said sheet bearing said areas together so that said areas are again in intimate face-to-face contact with one another.

10. The method of processing a photographic image-transfer product of the type comprising a pair of strips of sheet material each having an image receiving area thereon, said strips being arranged so that said image areas normally lie in substantial face-to-face contact with one another throughout the extent of said areas, one of said areas being photosensitive and the other being transfer-image-receptive, said method comprising:

exposing said photosensitive image area to produce a latent image therein; injecting between at least the image area-bearing portions of said strips a sufficient quantity of a processing liquid capable of initiating development of said photosensitive image area and image transfer therefrom to said transfer-image-receptive area to cause said areas to separate completely from one another throughout their extent; maintaining such liquid between said areas under a positive pressure for a predetermined period so that said liquid will hold said areas completely spaced from one another throughout said period; at the end of said period; relieving the pressure on said liquid; and pressing the image-area-bearing portions of said strips together so that said image areas are again in intimate face-to-face contact with one another to permit image transfer therebetween.

11. The method as set forth in claim 10 comprising the additional steps of:

maintaining said image areas in said last mentioned relationship for a second predetermined period to bring about the formation of a transfer image in said transfer-image-receptive area; and, at the expiration of said second period, separating at least that portion of the strip bearing said transfer image from said other strip.

12. The method of processing a photographic image transfer product including a photosensitive layer and a transfer-image-receiving layer comprising:

forming a fluid-tight chamber with the photosensitive layer carried on at least a portion of the inner face

of one wall of said chamber, and the receiving layer carried on the inner face of that wall portion directly opposite said sensitive layer, said chamber including flexible wall portions permitting relative movement between said layers; exposing said photosensitive layer to produce a latent image therein; injecting into said chamber a substantially free-flowing processing liquid capable of initiating processing of said exposed photosensitive layer and image transfer to said receiving layer; maintaining said liquid under sufficient pressure throughout said chamber to hold said opposed layers spaced materially apart from one another by said liquid for a predetermined period thereby substantially preventing image transfer therebetween during such period; and at the expiration of said period, relieving the pressure on said liquid; and pressing said opposing layers together into intimate face-to-face contact to force excess liquid from therebetween and to cause image transfer to said receiving layer.

13. The method of processing a photographic image transfer product including a photosensitive layer and a transfer-image-receiving layer providing negative and positive image areas respectively comprising:

forming a fluid-tight chamber, with the negative image area of said photosensitive layer carried on at least a portion of the inner face of one wall of said chamber, and the positive image area of said receiving layer carried on the inner face of that wall portion directly opposite said negative image area, said chamber including flexible wall portions permitting relative movement between said image areas, and at least one of said opposed wall portions being substantially transparent to light actinic to said photosensitive layer; exposing said negative image area of said photosensitive layer through said transparent wall portion to form a latent negative image in said image area; releasing into said chamber a substantially free-flowing processing liquid capable of initiating processing of said photosensitive layer and image transfer to said receiving layer; maintaining said liquid under sufficient pressure throughout said chamber for a predetermined period to hold said negative and positive image areas spaced apart from one another by said liquid so as to prevent image transfer therebetween during such period; and, at the expiration of said period, relieving the pressure on said liquid; and pressing said opposed walls together to bring said image areas into intimate face-to-face contact to force excess liquid from therebetween and to cause image transfer to said positive image area.

14. The method of processing a photographic image area comprising:

forming a fluid-tight chamber, at least a portion of the inner face of one wall of which comprises said area, said chamber including flexible wall portions permitting relative movement between said area and the opposing wall of said chamber; injecting into said chamber a substantially free-flowing

processing liquid capable of initiating the photographic processing of said image area; maintaining said liquid under sufficient pressure throughout said chamber to hold said area and said opposing wall spaced apart from one another by said liquid for a predetermined period; at the expiration of said period, relieving the pressure on said liquid; and pressing said area and said opposing wall together into intimate face-to-face contact to force excess liquid from therebetween.

15. The method of processing an exposed photographic image area, comprising:

forming a fluid-tight envelope with said image area on the inner surface of one wall thereof; injecting between said area and the opposing wall of said envelope a processing fluid capable of photographically processing said area; producing a positive pressure throughout said fluid by external pressure applied to portions of the envelope walls lying outside of the limits of said image area and in contact with said fluid, sufficient to hold said opposing wall spaced from said image area throughout the entire extent of the latter; maintaining said pressure for a predetermined processing period; at the end of said period, releasing said fluid from between said area and opposing wall; and pressing said area and opposing wall into intimate face-to-face contact throughout the extent of said area.

16. The method as in claim 15 wherein said positive pressure is produced by causing relative movement between said envelope and coacting external pressure applying means whereby said envelope wall portions are progressively forced into contact with one another beginning at a location spaced materially from said image area and moving relatively toward said image area until said pressure attains the desired value.

17. The method of claim 16 wherein said envelope includes a pressure rupturable seal securing the walls of said envelope together adjacent one edge of said image area; said fluid being released and said image area and its opposing wall being pressed together by resuming said relative movement of said envelope and said pressure means at the end of said period, thereby increasing the pressure within the fluid to a value sufficient to rupture said seal and to thereafter progressively force unabsorbed fluid from between said image area and its opposing wall and through said ruptured seal.
